UNITED STATES PATENT OFFICE.

HARRY E. PATRICK, OF EVANSTON, AND ANDREW J. PETERSON AND JOHN W. BERMES, OF CHICAGO, ILLINOIS, ASSIGNEES TO SERVICE STATION EQUIPMENT COMPANY, OF CHICAGO, ILLINOIS, A CORPORATION OF ILLINOIS.

PORTABLE ENGINE STAND.

Application filed October 27, 1919. Serial No. 333,681.

To all whom it may concern:

Be it known that we, HARRY E. PATRICK, ANDREW J. PETERSON, and JOHN W. BERMES, citizens of the United States, residing at 5 Evanston and Chicago, respectively, in the county of Cook and State of Illinois, have invented certain new and useful Improvements in Portable Engine Stands, of which the following is a specification.

10 Our invention relates to an apparatus suitable for use in connection with the assembling, disassembling or repair of internal combustion engines.

The invention in its broad aspect aims 15 to provide an improved apparatus of the above character with which an internal combustion engine, or parts thereof, may be conveniently transported from one department to another of a shop during the course of 20 the construction or repair of the engine, and which will present certain other advantageous features in connection with the application or removal of the engine from its operative position on a vehicle.

25 The invention more specifically contemplates the provision of an improved apparatus of the above character which will be particularly suitable for use in connection with the construction or repair of farm 30 tractor engines, particularly the engine used on the "Ford tractor", or in other situations where the engine, instead of being supported on the vehicle frame, is, in effect, a part of the frame. When applying 35 engines to vehicles of this type, it is necessary to accurately align the engine with the parts of the vehicle to which the engine is fastened and maintain the engine in such alignment until it is firmly bolted 40 in its operative position. It is also important to support the engine in alignment with the other portion of the vehicle body when disconnecting the engine from the body.

Prior to our invention various devices had 45 been employed for supporting the engine, such, for example, as overhead hoists. These devices have not been entirely satisfactory for the reason that it is difficult to effect the minute adjustment of the engine which is 50 usually necessary when applying it to the vehicle. In other instances, particularly in smaller shops which are not provided with overhead hoists and where it is impractical or undesirable to run the tractor into the

shop, the workmen have to resort to the 55 use of various forms of improvised supports for the engine.

Our invention aims to overcome the above and other difficulties in connection with the application of an engine to its operative 60 position or its removal therefrom by providing a simple and inexpensive apparatus which is provided with means whereby the engine may be accurately adjusted when the same is being applied to the vehicle and which 65 may be conveniently positioned under the engine so as to support the engine while it is being disconnected from the other parts of the vehicle, and in addition to the above features, to provide a truck which may be 70 conveniently used to transport the engine to the desired departments of the repair shop.

The invention consists in the novel arrangements, constructions and combinations 75 of parts hereinafter described and claimed for carrying out the above stated objects and such other objects as may appear from the following description of a preferred embodiment of the invention. 80

In the drawings,

Fig. 1 is a view illustrating the manner in which the apparatus is positioned under the engine of a tractor, the tractor illustrated being of the Ford type and is shown 85 in dotted lines in this figure.

Fig. 2 is a side view, in elevation, of the apparatus showing in dotted lines one of the side frames moved to its lower position so as to permit the apparatus to be 90 readily positioned under the engine.

Fig. 3 is a vertical section taken through the apparatus on line 3—3 of Fig. 5.

Fig. 4 is a fragmentary view, partly in section, illustrating the manner in which the 95 pivoted side frame of the apparatus is locked in its upright position.

Fig. 5 is a plan view of the apparatus, and

Fig. 6 is a side view of the same, the view being taken at right angles to Figs. 2 and 3, 100 and certain devices being omitted for the purpose of clearness.

Like characters of reference designate like parts in the several figures of the drawings.

Referring to the drawings, 10 designates 105 the base frame which is supported on casters 11. These casters are preferably provided with a ball bearing connection 12 (Fig. 2)

with the flanges 13 formed at the corners of the base 10. A rigid side frame 14 is secured at one edge of the base and preferably consists of corner posts 15 which may be bolted, as indicated at 16, or otherwise suitably secured to the base 10. The corner posts are connected and rigidified by means of cross braces 17, 17^a which are preferably formed integral with the corner posts. At 10 the opposite edge of the base is a pivoted frame 18 which consists of corner posts 19 secured together by means of cross pieces 20, 20^a in substantially the same manner as described in connection with the frame 14. 15 The lower ends of the corner posts 19 are bifurcated as indicated at 21 and fit over upstanding rigidifying ribs 22 formed on the base 10 and pivoted to said ribs by means of the pivoted pins 23. The lower 20 end of each of these corner posts is also preferably provided with an angular extension 24 which is similarly bifurcated and provided with an aperture which when the frame is in its upstanding position registers 25 with an aperture in the rigidifying rib 22. When the frame is in its upstanding position pin 25 may be inserted in said aperture so as to lock the frame in this position. The upper ends 26 of the corner posts 15, 19, are bifurcated as indicated at 27 so as to receive the dogs 28. These dogs are pivoted in the bifurcated portion, as indicated at 29, and are formed at their inner ends with lugs 30 on which the flange A of the engine crank 35 case B is seated. The other end of these dogs are provided with forks 31 which extend around threaded studs 32 extending outwardly from the frames 14, 18. Hand wheels 33 have threaded engagement with 40 the studs 32 and are adapted to bear against the forked end of the dogs 28 so that by turning the hand wheels down on the studs the angular position of the dogs 28 may be changed so as to vary the position of the 45 engine. Each of the dogs 28 may be separately adjusted and by this means a minute adjustment of the position of the engine may be accomplished.

Operation: When desiring to position the 50 apparatus under an engine of a vehicle, a Ford tractor, for example, the frame 18 is lowered to the dotted line position shown in Fig. 2. While the frame is in this position the apparatus may be readily pushed 55 under the engine and being provided with casters may be shifted to its proper position without difficulty. The pivoted frame 18 may then be raised to its upstanding position and locked in said position by means of 60 the pin 25. By turning the hand wheels 33 down on the studs 32 the angular position of the dogs 28 are changed so as to bear against the under surfaces of the crank case flanges A. While the engine is thus supported it may be readily detached from the

transmission case C by removing the bolts D. Before the bolts D are removed a suitable block E is placed under the transmission case so as to prevent it from dropping down. When the engine is supported on our apparatus the front wheels F and axle G may be readily removed and the engine, together with the radiator and other associated devices, moved into the shop for repairs, and as it is passed through each department of the shop the device to be repaired in that department is removed and the engine passed on to the next department. After the engine has been repaired and reassembled it may be again attached to the transmission case C. In order to accomplish this it is usually necessary to effect minute adjustment so that the crank shaft of the engine will accurately align with the other operating mechanism of the tractor 65 and so that the bolt holes of the engine and transmission case will register accurately. This result may be accomplished by manipulating certain of the hand wheels 33 so as to move the engine to the desired position. 70

While we have described our invention in one preferred embodiment, it will be obvious that modifications might be made without departure from our invention. We, therefore, do not wish to be limited to the exact 75 constructions shown and described except so far as specific limitations appear in the appended claims.

We claim:

1. A portable stand of the character described comprising a base, and opposite uprights, one of the latter being rigidly mounted upon the base and the other movably mounted thereon so as to raise and lower, whereby the stand can be moved under the engine of a tractor until its rigid upright is against the side thereof and the movable upright can then be raised against the other side of the engine; and the two uprights being equipped for the seating between them of the object to be supported such as said engine, and provisions being made for securing the movable upright in its raised position. 100

2. An engine supporting structure comprising a base, upstanding elements for supporting opposite sides of the engine, one of said elements being pivoted to the base whereby it may be lowered to permit the structure to be positioned under the engine 105 and subsequently raised to its engine supporting position, and adjustable means on said elements for varying the position of said engine. 110

3. An engine supporting structure comprising a base, wheels on which the base is mounted, an upstanding element rigidly connected to the base and adapted to extend adjacent one side of the engine, an upstanding element which extends adjacent the op- 115 120 125 130

posite side of the engine and having a hinged connection with the base whereby it may be lowered to permit the structure to be positioned under the engine, and engine supporting means pivotally connected with said upstanding elements and capable of adjustment so as to vary the position of said engine.

4. An engine supporting structure comprising a base, wheels on which the base is mounted, an upstanding element rigidly connected to the base and adapted to extend adjacent one side of the engine, an oppositely disposed upstanding element which extends adjacent the opposite side of the engine and having a hinged connection with the base whereby it may be lowered to permit the structure to be positioned under the engine, and a plurality of engine supporting devices pivotally connected with said upstanding elements and separately adjustable so as to vary the position of said engine.

5. An engine supporting structure comprising a base, wheels on which the base is mounted, an upstanding element rigidly connected to the base and adapted to extend adjacent one side of the engine, an oppositely disposed upstanding element which extends adjacent the opposite side of the engine and having a hinged connection with the base whereby it may be lowered to permit the structure to be positioned under the engine, means for securing said element in its upstanding position, and a plurality of engine supporting devices pivotally connected with said upstanding elements and separately adjustable so as to vary the position of said engine.

6. An engine supporting structure comprising a base having upstanding elements adapted to be positioned on opposite sides of the engine, separately adjustable engine supporting devices comprising threaded studs secured to said elements, dogs pivoted to the upper end of said elements and provided at one end with lugs on which the engine is seated and at the other end with forks which fit over said studs, and hand wheels on said studs for changing the position of said dogs so as to adjust the engine to the desired position.

7. An engine supporting structure comprising a base having upstanding elements adapted to be positioned on opposite sides of the engine, one of said elements being pivoted whereby the same may be lowered to permit the structure to be positioned under the engine and subsequently raised to its upstanding position, separately adjustable engine supporting devices comprising threaded studs secured to said elements, dogs pivoted to the upper end of said elements and provided at one end with lugs on which the engine is seated and at the other end with forks which fit over said studs, and

hand wheels on said studs for changing the position of said dogs so as to adjust the engine to the desired position.

8. An engine supporting structure comprising a base having upstanding elements adapted to be positioned on opposite sides of the engine, one of said elements being pivoted whereby the same may be lowered to permit the structure to be positioned under the engine and subsequently raised to its upstanding position, a pin for locking said element in its upstanding position, separately adjustable engine supporting devices comprising threaded studs secured to said elements, dogs pivoted to the upper end of said elements and provided at one end with lugs on which the engine is seated and at the other end with forks which fit over said studs, and hand wheels on said studs for changing the position of said dogs so as to adjust the engine to the desired position.

9. An engine supporting structure comprising a base formed on opposite sides with upwardly extending casters on which the base is mounted, a rigid end frame secured to the base, an oppositely disposed end frame comprising corner uprights formed at their lower ends with bifurcations which fit over said ribs and with an angular projection adjacent said bifurcated portion, means for pivoting said side frame to said ribs, means for securing said projecting portion to said ribs whereby the frame is locked in its upstanding position, and pivoted dogs at the upper end of the end frames adapted to support the engine and being capable of independent adjustment whereby the position of the engine may be varied.

10. An engine supporting structure comprising a base formed on opposite sides with upwardly extending casters on which the base is mounted, a rigid end frame secured to the base, an oppositely disposed end frame comprising corner uprights formed at their lower ends with bifurcations which fit over said ribs and with an angular projection adjacent said bifurcated portion, means for pivoting said side frame to said ribs, means for securing said projecting portion to said ribs whereby the frame is locked in its upstanding position, and pivoted dogs at the upper end of the end frames adapted to engage the flange of the lower section of an engine crank case and being capable of independent adjustment whereby the position of the engine may be varied.

11. An engine supporting structure comprising a base formed on opposite sides with upwardly extending casters on which the base is mounted, a rigid end frame secured to the base, an oppositely disposed end frame comprising corner uprights formed at their lower ends with bifurcations which fit over said ribs and with an angular projection adjacent said bifurcated portion,

means for pivoting said side frame to said ribs, means for securing said projecting portion to said ribs whereby the frame is locked in its upstanding position, and pivoted dogs

6 at the upper end of the end frames adapted to engage the flange of the lower section of an engine crank case and being capable of independent adjustment whereby the angu-

lar position of the engine with relation to the supporting structure or the height at 10 which the engine is supported may be varied.
